U.S. Cl. D6—167

FIG. 3

FIG. 2

FIG. 1

FIG. 1 is a front perspective view of a combined rotating display and storage unit showing my new design with the door to the storage area in the open position.

FIG. 2 is a rear perspective view.

FIG. 3 is a top plan view of FIG. 2.

The undisclosed front side of the door panel, except for the inclusion of the handle, is identical in appearance to the front side of the left panel in FIG. 2.

I claim:

The ornamental design for a combined rotating display and storage unit, as shown and described.
